HINGE JOINT

Filed March 5, 1931

INVENTOR.
HUGO STEIFF.
ATTORNEY: *R. Mandan*

UNITED STATES PATENT OFFICE

HUGO STEIFF, OF WURTTEMBERG, GERMANY

HINGE JOINT

Application filed March 5, 1931, Serial No. 520,353, and in Germany January 16, 1931.

The invention relates to hinge joints for the connection of members which are required to be capable of angular movement in relation to each other but to retain certain alternative positions when moved into those positions. It is a common practice to use for this purpose a spring catch on one of the members, arranged to engage a notch in the other member when the parts are in a particular position.

According to my invention one of the two members to be connected to each other by the hinge joint has two springy limbs, which are separately and pivotally connected to the other member at two different portions thereof, generally close together, so that the two members, when either of them is free to move, will only retain such relative positions as do not place the springy limbs under a stress which cannot be relieved by movement to a different position.

The invention is applicable to a great variety of purposes. One example is the attachment of limbs to the bodies of toy animals, and in this connection the invention is illustrated in the accompanying drawings, in which

Fig. 1 is an elevation of a toy dog, and

Fig. 2 an elevation of a toy penguin.

Fig. 3 is a side view, to a larger scale, but partly broken away, of a hinge used in the toy shown in Fig. 1;

Fig. 4 shows part of one of the hinge members, and

Fig. 5 is a plan view of this hinge.

Fig. 6 is a side view of a hinge used in the toy shown in Fig. 2, and

Fig. 7 is a face view thereof,

Fig. 8 showing part of one of the hinge members.

Each of the toy animals shown in Figs. 1 and 2 has a movable tail, connected to the body by a hinge having a member *a* within the body and a member *b* within the tail.

Referring to Figs. 3 to 5, and the toy dog shown in Fig. 1, the member *a* of the hinge is a rod of circular cross-section, flattened at one end to form a small plate *a*¹ (Figs. 3 and 4), in which there is a slot or a pair of holes *c*, the slot or the line connecting the

centers of the holes being in line with the axis of the rod *a*. The member *b* is a piece of springy wire, bent to form two side limbs having inwardly directed extensions *b*¹ overlapping each other, as best shown in Fig. 5. These extensions pass respectively through the holes *c*, or through the end portions of the slot, and are flattened at their ends *b*¹¹, to prevent withdrawal from the holes.

The part *a* is rotatable in the body of the animal and has a bent portion *a*¹¹ within the head, so that the head can be wagged by rocking the tail sideways.

In Fig. 3 one of the normal positions of the part *b* is shown in full lines, and the other normal position is shown in broken lines. By rocking the part *b* from the upper position, as indicated by an arrow, the springy limbs are stressed, resulting in distortion of the part *b*, more particularly by bending the extensions *b*¹ in opposite directions; this is due to the fact that the two limbs do not rotate about a common axis. Up to the time when the part *b* is in line with the part *a* the stress tends to make the part *b* swing back to its starting position. When in line with the part *a* the part *b* is in a dead center position, and does not tend to swing in either direction, but when moved past this dead center it tends to swing to the position shown in broken lines. The tail of the dog can thus be made to point upwards or to hang down.

It will be clear that when the hinge is not incorporated with the toy the part *b* can also be folded over towards the part *a*, and that it will then be practically in a dead center position, which it will retain unless disturbed.

In the modification shown in Figs. 6, 7 and 8 the slot, or the line connecting the centers of the holes *c*, is placed transversely of the axis of the part *a*. Consequently one of the normal positions of the part *b* is a position in alignment with the part *a*, as shown in full lines in Fig. 6. By rocking the part *b* from this position, as indicated in Fig. 6 by an arrow, the part is moved to dead center position approximately perpendicular to the part *a*. When moved past this position the part *b* tends to swing upwards. The tail of

the penguin shown in Fig. 2 can thus be made to retain the position in which it is shown in the drawings, or to retain a position in which it is folded upwards against the rump of the bird.

What I claim as my invention and desire to secure by Letters Patent of the United States is:—

A joint comprising two hinge members,
10 one of said hinge members being a substantially closed bail of spring material having two adjacent ends, the ends of the bail engaging the other hinge member at two separate pivot points adjacent each other, and
15 the inherent springiness of the bail tending to hold the same in either of two alternative end positions relative to said other hinge member, or in an intermediate dead center position, so that when the bail is moved from
20 either of said end positions, past said dead center position it will tend to move to the other end position.

HUGO STEIFF.
